Ser. No. 293,530, both Sept. 29, 1972, and Ser. No.
343,390, Mar. 21, 1973. This application June 14, 1974,
Ser. No. 479,458

Term of patent 14 years

Int. Cl. D21—02

U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a vertical sectional view, taken on the line 5-5 of FIG. 4, looking in the direction of the arrows.

FIG. 6 is a bottom plan view of FIG. 1.

FIG. 7 is a front elevational view of another embodiment of my design.

FIG. 8 is a front end view of FIG. 7.

FIG. 9 is a top plan view of FIG. 7.

FIG. 10 is a rear elevational view of FIG. 7.

FIG. 11 is a vertical sectional view, taken on the line 11-11 of FIG. 10, looking in the direction of the arrows.

FIG. 12 is a bottom plan view of FIG. 7.

FIG. 13 is a front elevational view of still another embodiment of my design.

FIG. 14 is a front end view of FIG. 13.

FIG. 15 is a top plan view of FIG. 13.

FIG. 16 is a rear elevational view of FIG. 13.

FIG. 17 is a vertical sectional view, taken on the line 17-17 of FIG. 16, looking in the direction of the arrows.

FIG. 18 is a bottom plan view of FIG. 13.

The characteristic feature of my design resides in the arcuate portions of the hosel in combination with the particular club head configuration shown.

This is a continuation of design patent applications D. 293,529 and D. 293,530, filed Sept. 29, 1972, and D. 343,390, filed Mar. 21, 1973, all now abandoned.

I claim:

The ornamental design for a golf putter head, as shown and described.
